FOREIGN PATENT DOCUMENTS

GB 2103708 S * 2/2001

Primary Examiner—T. Chase Nelson*(74) Attorney, Agent, or Firm*—Scott B. Markow(57) **CLAIM**

I claim the ornamental design for a pneumatic fastener, as shown.

DESCRIPTION

FIG. 1 is a top plan view of a pneumatic fastener showing my new design;

FIG. 2 is a front elevation view thereof;

FIG. 3 is a left side elevation view thereof;

FIG. 4 is a rear elevation view thereof;

FIG. 5 is a right side elevation view thereof; and,

FIG. 6 is a bottom plan view thereof.
